CLAIM

The ornamental design for an interlocking door seam, as shown and described.

DESCRIPTION

FIG. 1 is a perspective view of our interlocking door seam; FIG. 2 is a right side perspective view of our interlocking door seam of FIG. 1 shown in its context of use in conjunction with a mail delivery Cluster Box Unit (CBU), the CBU shown in phantom;

FIG. 3 is a top view of the interlocking door seam of FIG. 1;

FIG. 4 is a bottom view thereof;

FIG. 5 is a rear plan view thereof;

FIG. 6 is a front plan view thereof;

FIG. 7 is a left side plan view thereof; and,

FIG. 8 is a right side plan view thereof.

The phantom lines are shown for illustrative purposes only and form no part of the claimed design.
